Term of patent 7 years

(Cl. D52—3)

Fig.1.

Fig.2.

Fig.4.

Fig.3.

FIG. 1 is a front perspective view showing the front and one side of a product dispensing machine, showing our new design;

FIG. 2 is a front elevational view thereof;

FIG. 3 is a side elevational view showing the side opposite to that shown in FIG. 1;

FIG. 4 is a front perspective view showing the front and one side of a modified form of the product dispensing machine; and

FIG. 5 is an end elevational view of the product dispensing machine shown in FIG. 4, showing the side thereof opposite to that shown in FIG. 4.

The horizontal dash lines on the grill in FIGS. 1, 2, and 4 are intended to represent a continuation of the spaced rows of the short vertical lines.

The rear of the product dispensing machine of both

embodiments is substantially plain in appearance except for the presence of conventional access doors.

We claim:

The ornamental design for a product dispensing machine, substantially as shown and described.
